(57) CLAIM

The ornamental design for a toddler slide, as shown and described.

DESCRIPTION

FIG. 1 is a front, top perspective view of a toddler slide, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 1;

FIG. 10 is an enlarged view of detail "10" identified in FIG. 1;

FIG. 11 is an enlarged view of detail "11" identified in FIG. 1;

FIG. 12 is an enlarged view of detail "12" identified in FIG. 2; and,

FIG. 13 is an enlarged view of detail "13" identified in FIG. 2.

The dashed broken lines in the figures illustrate portions of the toddler slide that form no part of the claimed design. The dash dot dash broken lines in FIGS. 1, 2, 9, 10, 11, 12 and 13 are for the purpose of illustrating the bounds of the enlarged views and form no part of the claimed design.

1 Claim, 13 Drawing Sheets
